UNITED STATES PATENT OFFICE.

DAVID AUSTIN HENSLEY, OF VICKSBURG, MISSISSIPPI, ASSIGNOR OF ONE-
FOURTH TO ROBERT A. QUIN, OF SAME PLACE.

SPACE-BAR FOR LINOTYPE-MACHINES.

SPECIFICATION forming part of Letters Patent No. 669,831, dated March 12, 1901.

Application filed May 18, 1900. Serial No. 17,117. (No model.)

To all whom it may concern:

Be it known that I, DAVID AUSTIN HENSLEY, a citizen of the United States, and a resident of Vicksburg, in the county of Warren 5 and State of Mississippi, have invented a new and Improved Space-Bar for Linotype-Machines, of which the following is a full, clear, and exact description.

My invention relates to the wedges or space-bars which are used in linotype-machines to fill the spaces between the matrices so as to justify the line.

The object of my present invention is to provide a space-bar for the above-indicated purpose which will be strong and light and the parts of which will be securely connected and reliably guided upon one another. To this end I construct the space-bar as will be fully described hereinafter and particularly 20 pointed out in the claims.

Reference is to be had to the accompanying drawings, forming a part of this specification, in which similar characters of reference indicate corresponding parts in all the figures.

25 Figure 1 is an edge view of my improved space-bar. Fig. 2 is a perspective view thereof. Fig. 3 is a face view of the bar; and Figs. 4, 5, 6, and 7 are sectional plans on lines 4 4, 5 5, 6 6, and 7 7, respectively, of Fig. 3.

30 The improved space-bar consists of two parts or wedges, the upper one of which I will term the "stationary" member, inasmuch as it is held against upward movement in the ordinary manner, while the lower part 35 will be termed the "movable" member, as it is driven up by the usual or any approved mechanism for the purpose of expanding the space-bar.

The movable member consists of a wedge-40 section A, tapering from the bottom to the top and provided with a longitudinal opening or slot A', the edges of which are beveled so as to form a dovetail slideway A². The direction of this slideway is parallel with the 45 inclined inner face of the section A. This slideway is continued to the bottom of the section A, the central portion of which below the slot A' is for this purpose of reduced thickness, as shown at A³.

50 A⁴ is the customary aperture into which

fits a guide-bar engaging the space-bars on their way to the space-bar box.

On the front face of the wedge-section A, with inserted thin liners, is secured, as by means of rivets C, a shield-section B of substantially the same outline as the section A, and also provided with a slot, B' corresponding in size and location to the slot A', except that the slot B' is continued downward below the lower end of the slot A'. The shield B is 60 of spring-steel and of uniform thickness from top to bottom. The edges of the slot B' are beveled to form a dovetail slideway B².

The stationary member of the space-bar is arranged between the movable wedge A and 65 the shield B and has sliding engagement with both. This member has the customary ears or lugs D to guide the space-bar in its movement and to hold the said member stationary when the space-bars are being expanded. The 70 central portion of the stationary member is reduced in thickness, as shown at D' D², the recess in the front face being equal in depth to the thickness of the shield B, so that said shield will be flush with the ears D and D⁶. 75 The recess D² in the rear side forms a guide for the movable wedge A and is equal in depth to the thickness of the top of the wedge A, so that the top of said wedge will be flush with the ears D and D⁶. The central portion of 80 the stationary member is wedge-shaped, being tapered from top to bottom—that is, in the opposite direction to the wedge A. The stationary wedge has on its rear face a plate D⁸, the edges of which are beveled to fit into the 85 dovetail A² of the movable wedge A. On the front face of its web D⁵ the stationary wedge is provided with a thickened portion or plate D⁴, the longitudinal edges of which are beveled to take into the dovetail B' of the shield 90 B. The lower end of the plate D⁸ of the stationary wedge may, if the movable member of the wedge is pushed up far enough, come in registry with the reduced portion A³ of the wedge A or nearly so, and to prevent the stationary member from binding between the wedge and shield when pushed up thin liners are inserted between them and held by means of rivets C.

95 The operation of my improved space-bar is 100

the same as that of ordinary space-bars for linotypes. Superior results are obtained, however, owing particularly to the fact that the shield B is of uniform thickness instead of being wedge-shaped, as in other constructions known to me. Further, the stationary wedge has a dovetail or equivalent connection not only with the shield, but with the movable wedge also, so that it is impossible for either the movable wedge or the shield to spring away from the stationary wedge or to move transversely or edgewise in relation thereto. The formation of guides D' D² for the shield and the movable wedge on the upper part of the stationary wedge assists in keeping the members of the space-bar in proper alinement and in securing an easy motion, while at the same time the weight of the space-bar is reduced.

20 My purpose in employing two sets of lugs D D⁶ is to divide the work of guiding the space-bars in their travel through the machine between these lugs, causing them to engage successively the several guiding-surfaces of the machine, so as to reduce wear.

25 Having thus described my invention, I claim as new and desire to secure by Letters Patent—

1. A space-bar for linotype-machines, comprising a movable wedge tapering from bottom to top and provided with a dovetail, a shield of uniform thickness secured to the bottom of said wedge and provided with a longitudinal dovetail, and a stationary wedge 35 tapered from top to bottom and arranged between the shield and the movable wedge and in sliding engagement with their dovetails.
2. A space-bar for linotype-machines, comprising a movable wedge tapering from bottom to top and provided with a dovetail, a shield of uniform thickness secured to the bottom of said wedge and provided with a

longitudinal dovetail, and a stationary wedge tapered from top to bottom and arranged between the shield and the movable wedge, said stationary wedge having upon its front face and upon its rear face, plates or projections with beveled longitudinal edges to fit the dovetails of the movable wedge and of the shield.

3. The combination of the movable member of the space-bar, said member consisting of a rear wedge-section and a front shield-section connected at one end and spaced at the other, and a stationary wedge member located 55 between the said rear wedge and shield and having with each of them an engagement which allows of longitudinal sliding movement but prevents the shield and rear wedge from spreading away from the stationary wedge.

4. The combination, in a space-bar for linotype-machines, of a movable member consisting of a rear wedge-section and a front shield-section of uniform thickness from top to bottom, said sections being connected at one end and spaced at the other, and a stationary wedge having a sliding connection with the movable member and arranged between the sections thereof.

5. In a space-bar for linotype-machines, the combination of a movable member consisting of two sections connected at one end and spaced at the other, with a stationary wedge fitted to slide between said sections 75 and recessed in its face to form guideways for the free or spaced ends of said sections.

In testimony whereof I have signed my name to this specification in the presence of two subscribing witnesses.

DAVID AUSTIN HENSLEY.
